UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

POSITIONING DEVICE FOR CAR COUPLERS.

Original application filed June 16, 1926, Serial No. 116,408. Divided and this application filed October 29, 1927. Serial No. 229,657.

This device relates to means for automatically positioning the coupler of a railway car by gravity.

Two railway cars are automatically coupled together by the movement of their respective couplers forcing the tails of the pivoted knuckles behind gravity locks. The couplers are mounted in the cars so as to permit a limited amount of lateral movement. Such limitation is necessary and essential because if the couplers were allowed to move too far to either side, the couplers of the two cars being coupled would pass each other and not couple, thereby defeating the object of the automatic coupler. The greater the lateral movement of a coupler the less side pressure on the striking casting when the cars are going around curves. This lateral pressure forces the wheel flanges against the rail causing considerable friction and wearing of the rails and wheels.

One of the objects of the invention is to increase the amount of permissible lateral movement of a coupler by providing automatic means for returning the couplers to the longitudinal center of the car or at least close enough thereto so that the automatic couplers will couple. This is what is termed the "coupling range."

It is very often necessary to couple cars on curves and frequently when the radius of the curve is very small, as is common around industrial plants, the couplers of the two cars will be so far out of alignment that they will not automatically couple. Another object of the invention is to automatically bring such couplers within coupling range. The outside rail of a curved track is raised above the inside rail and I provide means whereby the coupler is moved toward the inside of the curve by gravity. This automatic gravity means also returns the coupler to the longitudinal center of the car when the car moves from the curved to the straight part of the track.

In my device the lateral movement between the coupler and the carrier is eliminated, thus reducing friction and consequent wear on the parts. This is quite an item particularly in sandy countries because couplers are costly and the replacement of a coupler means keeping the car out of service.

Coupler positioning devices reduce the number of broken knuckles and guard arms

on couplers which members are frequently bent or broken when the couplers are not within coupling range. Such devices also reduce the number of accidents to trainmen as they are not required to go between the cars and position the coupler preparatory to coupling.

A common form of car coupler positioning device comprises a coupler carrier swingably suspended by links from some part of the car so that the objects and advantages mentioned above are obtained and my invention is an improvement upon such devices and consist in providing a shiftable bearing construction to increase the eccentricity of the weight of the coupler (and its associated parts) about its point of support, thus increasing the resultant force tending to return the coupler to the longitudinal center of the car (or away therefrom when the car is tipped.) I accomplish this result without necessarily increasing the vertical rise of the coupler. This is important because the A. R. A. standard dimension only permits $\frac{3}{4}$ " vertical rise of the coupler.

In my device the coupler carrier is swingably suspended from any convenient part of the car by a link at each of its ends and is provided with means such as lugs to prevent lateral movement of the coupler relative thereto. At least one of these links has spaced apart portions both supporting the link (and its load) when it is in its normal central position. When the carrier swings in one direction, one of the portions moves away from its support, thus shifting the load upon that link entirely to the other portion. A similar action takes place when the carrier swings in the opposite direction. It is preferable that the carrier maintain a horizontal position at all times, which is accomplished by arranging the links so that a vertical line passing through the pivot connection of the link bisects the distance between the spaced apart portions of the link. When the shiftable bearing construction is used at both ends of a link, the parts are arranged so that a vertical line bisects the distances between the pairs of spaced apart elements.

The shiftable bearing construction may be used on one or both ends of one or both links. It may be used to function on one link when the carrier moves in one direction and upon

- the other link when the carrier moves in the other direction, or it may be applied to one end of one link to function when the link swings in either direction. Furthermore, the shiftable bearing construction may be arranged with contacting points or lines between the link and car part or between the link and the carrier, but a journaled bearing is preferable to provide greater bearing area.
- 10 In a journaled arrangement, the journal may be on the car part and the journal bearing on the link or vice versa, or in fact, the link may have a journal and a journal bearing engaging a journal bearing and journal, respectively, on the car part.

Another object is to form such a link that it automatically stabilizes itself and the device against movement of the coupler longitudinally of the car, and, furthermore, to proportion such a link that it may be formed from a commercially rolled rectangular steel bar.

In the drawings:

Fig. 1 shows a typical application of my device to a railway car.

Fig. 2 is a section on line 2—2 of Fig. 1.

Fig. 3 is a side elevation of Fig. 1.

Figs. 4 and 5 are skeleton diagrams showing the device, respectively in normal position and with the carrier moved laterally.

Fig. 6 is a detail of the carrier.

Fig. 7 is a detail of the link.

Fig. 8 shows a modified form of the link.

Fig. 9 is a section on line 9—9 of Fig. 8.

35 Figs. 10 and 11 are skeleton diagrams showing a modified form of the device, respectively when the carrier is in normal position and with the carrier moved laterally.

Fig. 12 is a detail of the link shown in Figs. 10 and 11.

40 Figs. 13 and 14 show modified forms of the link shown in Fig. 12.

In the arrangement shown in Figs. 1 to 9, inclusive, the double bearing construction is used at the lower ends of the links and the upper ends of the links are pivoted at a part of the car. A journaled construction is shown. When the coupler 2 is in its normal central position (as shown in Fig. 1) the journal bearing 3 on the carrier 4 engages the journal 5 on the link 6 and at the same time the journal bearing 7 on the link engages the journal 8 on the carrier. When the coupler moves distance "A" to the right (as shown in Fig. 5) the journal bearing 3 on the right end of the carrier moves away from the journal 5 on the link so that the right end of the carrier is entirely supported by the journal 8 of the carrier resting upon the journal bearing 7 of the link.

45 The eccentricity or lever arm of the load on this link is the horizontal distance "C" between parallel vertical planes 10—11 passing, respectively, through the upper pivot 12 and the contact line between the journal 8 on

the carrier and the journal bearing 7 on the link. At the same time the journal 13 on the left end of the carrier moves away from the journal bearing 14 on the link so that the left end of the carrier is entirely supported by the journal bearing 15 of the carrier resting upon the journal 16 of the link. The eccentricity of the load on this link is the horizontal distance "B" between parallel vertical planes 17—18, one of which passes through the upper pivot 19 and the other of which passes through the contact line between the journal bearing 15 of the carrier and the journal 16 of the link. There is no eccentricity when the device is in normal position because a vertical plane 30 passing through the upper pivot 12 passes between the two contacting lines 3—5 and 7—8 of the connection between the link and the carrier. Of course, the link could be reversed and still obtain the desired results, i. e., the carrier could be pivoted to the link and the double bearing construction used between the link and the car part.

50 In the usual centering device link, which is pivoted at both ends, the eccentricity of the load upon the link is equal to lateral swing (A) of the carrier, but in my arrangement this eccentricity is increased by one-half the distance between the spaced apart bearings. In other words, when the carrier moves distance "A" (Fig. 5) both "B" and "C" are 55 greater than "A".

55 This shifting of the bearing moves the center of the effective radius of the link and the parts may be so proportioned as to maintain the same radius or to increase or decrease it, as desired. In any event, however, the eccentricity of the load about its support is increased. Decreasing the effective radius increases the vertical rise of the car in a given amount of lateral movement, while increasing the effective radius decreases the said rise. The effective radii of the right and left link, respectively, are shown at "D" and "E" in Fig. 5.

60 Fig. 6 shows the carrier of the form shown in Figs. 1—5, inclusive. The semi-cylindrical projections form the journals 8—13 and the semi-cylindrical depressions 3—15 form the journal bearings.

65 Fig. 7 shows the link 6 of Figs. 1 to 5, inclusive, in detail. The upper hook 21 engages the pivot 12 and is made wide to stabilize the link. The lower hook 22 forms the double bearing construction wherein the inside of the hook forms the journal bearing 7 and its end is rounded to form a journal 5. As the load is sometimes applied at the end of this lower hook (the journal) it must be quite strong through the open part of the hook which is accomplished by increasing its vertical thickness at the desired place. The horizontal width is proportionately decreased so that the link may be made of a commercially rolled rectangular bar by sim- 70 75 80 85 90 95 100 105 110 115 120 125 130

ply squeezing it into the desired varying width and varying depth and then forming the hooks.

When the link is made from a metallic bar 5 it may be strengthened and stiffened by an integral rib or corrugation 23 which extends through the major part of the hook and terminates (24) within the bar so as not to interfere with the journal. If a hook is merely 10 used to engage a pivot the rib may extend through the entire hook. This corrugation also reinforces the shank 25 when possible, as shown in Fig. 8. Fig. 9 shows the rib.

Fig. 4 shows the device when the coupler is 15 in normal position and Fig. 5 shows the device with the coupler moved laterally. In these figures the immaterial parts of the car have been omitted.

Figs. 10-13, inclusive, show a modification 20 wherein the double bearing construction is used on both ends of the links 39. The action at the bottom of the link is the same as heretofore described, and a similar action takes place at the top of the link. When the 25 carrier moves a distance "F" (Fig. 11) to the right the journal bearing 31 on the upper end of the right link leaves the journal 32 on the car part (33) thus shifting the entire load on this link to its upper journal 34 which is supported by the journal bearing 35 on the car part. At the same time, the journal 36 on the upper end of the left link leaves the journal bearing 37 on the car part 33, thus shifting the entire load on the left 35 link to its journal bearing 38 which is supported by the journal 49 on the car part.

The eccentricity of the load on the link is 40 the horizontal distance between parallel vertical planes, one of which (40) passes through the contact line of the car part and the link and the other of which (41) passes through the contact line of the link and the carrier. In the usual centering device link, which is pivoted at both ends, the eccentricity of the 45 load upon the link is equal to the lateral swing "F" of the carrier, but with this two-fold double bearing arrangement the eccentricity is increased by half the distance between each pair of spaced apart bearings. 50 In other words, when the carrier moves a distance "F" (Fig. 11) both "G" and "H" are greater than "F". There is no eccentricity when the device is in normal position because a vertical plane 42 passes between the upper spaced apart portions 31-32 and 34-35 and also passes between the lower spaced apart portions 3-5 and 7-8.

Fig. 12 shows the link 39 of the form shown in Figs. 10 and 11. Figs. 13 and 14 55 show a link 43 and 44 with the hook ends bent in opposite directions. In Fig. 14 a vertical plane (45) passes through the opposite journal bearings 46-47, while in Fig. 13 a vertical plane (48) passes midway be-

tween the journal and journal bearing at 65 each end of the link, or broadly speaking, the spaced apart portions.

There are certain advantages to be obtained by arranging the spaced apart portions of the link so that one of them is out of 70 contact when the coupler is in normal position, but which functions after a predetermined amount of swing of the link. Such a construction is covered by application for patent Serial No. 116,406, filed June 16, 1926. 75

In the device covered by this application the load is shifted from one bearing to another by the lateral movement of the carrier. There are certain advantages in having a gradual shifting of the bearing which are accomplished by a rolling engagement between the link and the car part (or carrier) which is covered by application for patent Serial No. 116,407, filed June 16, 1926.

This is a division of my co-pending application Serial No. 116,408, filed June 16, 1926.

The accompanying drawings illustrate the preferred form of the invention, though it is to be understood that the invention is not limited to the exact details of construction shown and described, as it is obvious that various modifications thereof within the scope of the claims will occur to persons skilled in the art.

I claim:

1. In a railway car; the combination of a car part element, a coupler carrier element, and a pair of links swingably suspending the opposite ends of the carrier thereto, said links having an inwardly projecting hook at 100 each end thereof, the ends of the hooks forming journals engageable with bearings in the car part and carrier, respectively, the hooks at the upper ends of the links being wider than the lower hooks.

2. In a railway car; the combination of a car part, a coupler carrier, and a pair of links swingably suspending the opposite ends of the carrier thereto, each of said links comprising a shank with a hook at each end forming a journal bearing, one of said hooks being relatively wider and relatively thinner than the other of said hooks, the ends of the hooks forming journals engageable with bearings in the car part and carrier, respectively, and the inside of said hooks forming bearings engageable with journals in the car part and carrier, respectively.

3. As an article of manufacture, a link for a car coupler positioning device comprising a shank with a hook at each end forming a journal bearing with each end rounded to form a journal, one of said hooks being relatively wider than the other of said hooks.

4. As an article of manufacture, a link for a car coupler positioning device comprising a shank with a hook at each end forming a journal bearing with each end rounded to

form a journal, one of said hooks being relatively wider and relatively thinner than the other of said hooks.

5. As an article of manufacture, a link for a car coupler positioning device comprising a shank with a hook at each end forming a journal bearing with each end rounded to form a journal, one of said hooks being relatively wider and relatively thinner than the other of said hooks, the cross sectional areas of the link being equal to each other.

6. As an article of manufacture, a link for a car coupler positioning device comprising a shank with a hook at each end, one of said hooks being relatively wider than the other of said hooks.

7. As an article of manufacture, a link for a car coupler positioning device comprising a shank with a hook at each end, one of said hooks being relatively wider and relatively thinner than the other of said hooks.

8. In a railway car; the combination of a car element, a coupler carrier element, and a pair of links swingably suspending the opposite ends of the carrier thereto, said links having a hook at each end thereof, the ends of the hooks forming journals engageable with bearings in the car part and carrier, respectively, the hook at one end of each link being relatively wider than the hook at the other end of the same link.

9. In a railway car; the combination of a car element, a coupler carrier element, and a pair of links swingably suspending the opposite ends of the carrier thereto, said links having a hook at each end thereof, the ends

of the hooks forming journals engageable with bearings in the car part and carrier, respectively, the hook at one end of each link being relatively wider and relatively thinner than the hook at the other end of the same link.

10. In a railway car; the combination of a car element, a coupler carrier element, and a pair of links swingably suspending the opposite ends of the carrier thereto, said links having a hook at each end thereof, the hook at one end of each link being relatively wider than the hook at the other end of the same link.

11. In a railway car; the combination of a car element, a coupler carrier element, and a pair of links swingably suspending the opposite ends of the carrier thereto, said links having a hook at each end thereof, the hook at one end of each link being relatively wider and relatively thinner than the hook at the other end of the same link.

12. In a railway car; the combination of a car part, a coupler carrier, and a pair of links swingably suspending the opposite ends of the carrier thereto, each of said links comprising a shank with a hook at each end forming a journal bearing, one of said hooks being relatively wider than the other of said hooks, the ends of the hooks forming journals engageable with bearings in the car part and carrier, respectively, and the inside of said hooks forming bearings engageable with journals in the car part and carrier, respectively.

ARTHUR E. SMALL.
